UNITED STATES PATENT OFFICE.

GEORGE TURNER, OF KALAMAZOO, MICHIGAN.

WINDMILL.

SPECIFICATION forming part of Letters Patent No. 339,715, dated April 13, 1886.

Application filed January 21, 1886. Serial No. 189,277. (No model.)

To all whom it may concern:

Be it known that I, GEORGE TURNER, a citizen of the United States, residing at Kalamazoo, county of Kalamazoo, State of Michigan, have invented a new and useful Power-Windmill, of which the following is a specification.

The object of this invention consists in the improved means of connecting working machinery to be driven by a single vertical rotatable power-shaft of a windmill with said shaft, substantially as below described and claimed, to prevent the resistance of the working machinery from causing the wind-wheel to creep out of its true position in the wind.

In the drawings forming a part of this specification, Figure 1 is an elevation, with the mill-head and tubular pendant in vertical section; Fig. 2, a section on line 2 in Fig. 3; Fig. 3, a top view of the detail shown in Fig. 2; and Fig. 4, a part of Fig. 3, referred to by like letters.

Referring to the letters marked on the drawings, B is an ordinary mill-head, with tubular pendant E, having swiveled bearings in the cap of the derrick F, in the usual manner. The horizontal wheel-shaft D has bearings in the mill-head, and is provided with a rigidly secured gear, a, which meshes with the gear c at the top of the vertical power-shaft r. The pendant E has a vertical tubular extension, f, through which the power-shaft r passes. To the lower end of the extension f is rigidly secured a laterally-extending pinion-support, R, or bridge-tree. The outer end is turned under and forms an upper and lower bearing for the pinion C, Fig. 1. The lower end of the power-shaft r has a pinion, A, meshing with the pinion C.

When the wind-wheel rotates, motion is transmitted from the wheel-shaft to pinion C. It will be observed that when the mill-head turns in its swiveled bearings in the top of the derrick, which is caused by the wind-wheel shifting in the wind from one point of the compass to another, the pinion C is swung around to a greater or less degree, describing some portion of a circle, according to the distance the mill-head turns; hence said pinion C is always in meshing relation with the gear A of the power-shaft r.

It is desired that motion be transmitted from

the pinion C to machinery having fixed or grounded bearing-supports. For the purposes of this description the gears t' t and shaft s at the lower end of Fig. 1 will serve to illustrate such machinery, while it should be understood that the exact details of the gear-connection of parts in this invention need not necessarily be followed. As the gear C fluctuates from one point to another around or partly around the axis of the shaft r, I connect the axle of the pinion C with the axle of the pinion t by means of a flexible shaft, P. I term this shaft "flexible" because it performs the function in this construction which a flexible shaft proper would perform, and hence such latter shaft might be employed. The shaft P has double joints at each end at right angles to each other, enabling it to yield and swing in all necessary directions. The square end of the rod P adjustably slips in and out in the joint x, Fig. 1, thus enabling the shaft to lengthen and shorten when necessary. To illustrate: if the gear t were not in line with the vertical axis of the power-shaft r, then it would be necessary that the shaft r be capable of lengthening and shortening.

During the operation the upper end of the shaft P follows the sweeping movement of the pinion C when the wheel changes in the wind. At the same time the connected pinion C, shaft P, and gear t' rotate together, imparting motion to the machinery having the fixed bearings below the same, as though the pinion C had fixed bearings, and it was not necessary for the wind-wheel to shift in the wind.

In Figs. 2 and 3 it will be seen that the pinion-support R has an oil-cup, u, formed in the top, with oil-passages ee leading to the bearing of the shaft r and to the upper bearing of the pinion C. By keeping the cup u filled with oil these bearings are always lubricated. Other details and general operation of power-windmills are well understood without further description here.

Having thus described my invention and its relation and operation with ordinary power-windmills, what I claim as new, and desire to secure by Letters Patent of the United States, is—

1. In a power-windmill, the combination of a power-shaft and its lower gear, said shaft passing through and being rotatable in a verti-

cal extension of the mill-head, a pinion-support secured to said extension, extending laterally therefrom and bearing a pinion meshing with the gear of the power-shaft, a machine-
5 gear having a grounded bearing, and a shaft connecting with the axle of said pinion and the latter-named gear, substantially as set forth.

2. In a power-windmill, a shaft having a
10 pinion attached to its upper end by a universal joint, said pinion having bearings in a support connecting with the mill-head, and meshing with a gear attached to the vertical power-

shaft of the mill, the lower end of the first-named shaft being connected by a universal 15 joint with machinery having a grounded bearing-support, all combined substantially as set forth.

In testimony of the foregoing I have hereunto subscribed my name in presence of two 20 witnesses.

GEORGE TURNER.
